UNITED STATES PATENT OFFICE.

CASPER P. SEITZ, OF HAYS, KANSAS.

THEFT ALARM.

Application filed February 16, 1927. Serial No. 168,792.

This invention relates to new and useful improvements in attachments for automobiles, and particularly to devices by means of which such automobiles may be secured 5 against theft.

One object is to provide a device which may be easily applied to an automobile, and which is adapted to be actuated by a moving part of the automobile, whereby to sound 10 a signal, which will warn others of the fact that the automobile is being driven by a person other than the rightful owner.

Another object is to provide a device of this character which will continue to sound 15 the alarm, should an attempt be made to stop such alarm, by destroying certain parts of the device.

Other objects and advantages will be apparent from the following description when 20 taken in connection with the accompanying drawings.

In the drawings:

Figure 1 is a side elevation of the invention and such parts of the automobile as are 25 necessary to impart a clear understanding of the location thereof.

Figure 2 is a vertical longitudinal sectional view through the invention, showing the parts in normal or neutral position, the 30 dotted lines indicating the position of the parts when the device is ready to give the alarm, should the automobile be set in motion by an unauthorized person.

Figure 3 is a vertical sectional view on the 35 line 3—3 of Figure 2.

Figure 4 is a detail view showing the latching means 41 in operative position.

Referring particularly to the accompanying drawing, 10 represents a portion of the 40 instrument-board, 11 a portion of the fly-wheel housing, and 12 a portion of the fly-wheel, of an automobile, in connection with which the present invention is particularly adapted for use.

Properly secured within an opening 13, in the instrument-board 10, and projecting forwardly therebeyond, is a casing 14, the forward end of which is provided with a tube 15, leading to and passing through an opening 45 in the fly-wheel housing 11. Connected to the forward end of the tube 15, within the housing 11, is a cup 16, the end remote from its connection with the tube being closed by a diaphragm 17. Within this cup, and bearing 50 against the tube attached end thereof, and against the diaphragm, is a coil spring 55

18, which normally urges the diaphragm into the full line position of Figure 2. Properly secured within the casing 14, and in concentric spaced relation thereto, is a cylindrical member 19, the inner end of which is closed by the diaphragm 20, while the other end is closed by the hollow head 21, said hollow head having a communication with the space between the cylinder and the casing 60 by means of the openings 22. Secured to the head 21, and disposed within the cylinder 19, is a lock including the spring pressed 65 latch-bolt 23, which projects toward one side of the cylinder, as clearly seen in the sectional view Fig. 2. A key-hole 24 is formed centrally in the head 21 to permit the owner to release the latch-bolt, when desired. Slidable through the said head 21 is a rod 25, the outer end of which is provided with a 70 button 26, to be grasped by the operator, while the inner end is extended toward the center of the cylinder where it is secured to the center of the diaphragm 20. In the longitudinally extending portion of the rod 25 75 there is formed a notch or recess 27, into which the nose of the latch-bolt 23 is adapted to engage, when said rod is pulled outwardly the required distance.

Mounted in the housing 11, adjacent the 80 fly-wheel 12, is a bracket 28, in which is supported the rock shaft 29. One end of the rock shaft is provided with a crank arm 30 which is properly connected with a stem 31, and which stem is secured in the center of 85 the diaphragm 17. The other end of the shaft 29 is formed with a radially extending arm 32, which is terminally formed with an angularly extending tubular member 33, within which is rotatably disposed a shaft 90 34. Connected with one end of the tubular member 33 is a horn casing 35, within which is arranged the diaphragm 36, of the horn, and mounted on the adjacent end of the shaft 34 is a head 37 which is adapted 95 to operate to vibrate the diaphragm, upon rotation of the shaft. On the other end of the shaft 34 is secured a small wheel 38 which is adapted to be brought into engagement with the periphery of the fly-wheel 12, 100 in the operation of the invention. Fixed on the shaft 29, inwardly of the crank arm 30, is a cam 39. Supported in the bracket 28, beneath the shaft 29, is a small rock shaft 40, one end of which is formed with a crank 105 arm 41 disposed in the path of the said cam 39, while the other end is held by means of

a spring 42. It is to be understood that a vacuum exists within the casing 14, the tube 15, and the cup 16, which is strong enough to permit the diaphragm 17 to assume its normal position of the full lines of Fig. 2 against the tension of the spring 18. This position also maintains the wheel 38 out of engagement with the fly-wheel 12.

When the owner desires to place his automobile in a condition whereby an alarm will sound, when the automobile is being operated by an unauthorized person, he simply grasps the button 26, and pulls the rod 25 out until the latch 23 snaps into the recess 27. This movement of the rod 25 flexes the diaphragm 20 inwardly toward the instrument board, which in turn affects the diaphragm 17, so that the latter is bowed inwardly toward the spring 18, thus compressing said spring. This movement of the diaphragm 17 actuates the stem 31, whereby to rock the shaft 29 in one direction to cause the wheel 38 to engage with the fly-wheel. When the motor is set in motion, the fly-wheel will drive the wheel 38, and the shaft 34, so that the head 37 causes the diaphragm 36 to vibrate, and sound the alarm. Should the thief be unfamiliar with the device, he will be unable to stop the horn, as such horn, as well as the other parts of the device are so located as to be difficult to reach, especially in such haste as the thief would be. The continuous sounding of the horn would indicate to other persons that the automobile was being stolen, and rather than be caught, the thief would abandon the car. Should, however, the thief know that vacuum played an important part in the operation of the device, he might puncture the device at such a point as to destroy the vacuum, with the hope that this might render the device inoperative. This would be futile, for, upon breaking the vacuum, the spring 18 would immediately expand to flex the diaphragm 17 outwardly, with the result that the shaft 29 would be rocked in the opposite direction, causing the wheel 38 to engage with the fly-wheel. As the shaft 29 rotates in such direction the cam 39 engages with the crank arm 41, to rock the shaft 40, whereby subsequently the said crank arm will engage with the cam to hold the shaft against return rocking movement. Thus the parts would set the horn in operation again. If the thief should attempt the release by the use of a pump, all he would accomplish would be to further flex the diaphragms 17 and 20.

Upon proper manipulation of a key, in the key-hole 24, the owner can release the latch 23 from the rod 25, whereupon the diaphragms 17 and 20 will assume their normal neutral positions, so that the automobile may be operated without sounding the horn.

What is claimed is:

1. The combination with a moving part

of a vehicle, of an audible signal including a rotating actuating part, vacuum controlled means for moving the rotating part into and out of engagement with said moving part, and means movable into and out of engagement with the vacuum controlled means for holding the rotating part in engagement with the moving part whereby to cause the continuous sounding of the signal, at times, and for holding the rotating part out of engagement with the moving part, to render the signal inactive at times.

2. The combination with a moving part of an automobile, of an audible signal including a horn and a member arranged to be actuated by said moving part to sound the horn, vacuum controlled means for maintaining the said member out of engagement with the moving part, and means for moving the vacuum controlled means whereby to engage said member with said moving part.

3. The combination with a moving part of an automobile, of a horn including a diaphragm, means movable into and out of engagement with said moving part for vibrating the diaphragm, means normally holding the movable means out of engagement with the moving part, and vacuum controlled means for moving said movable means into engagement with said moving part.

4. The combination with a moving part of an automobile, of an audible signal including an actuating part movable into and out of engagement with said moving part, vacuum controlled means for maintaining said actuating part out of engagement with the moving part, and means for moving the vacuum controlled means to engage said actuating part with said moving part.

5. The combination with a moving part of an automobile, of an audible signal including an actuating part adapted to be moved into and out of engagement with said moving part, means holding the actuating part normally out of engagement with the moving part, vacuum chambers, diaphragms in the chambers, connections between said actuating part and one of the diaphragms, and means for moving the other diaphragm whereby to actuate the first-named diaphragm to move the actuating part into engagement with the moving part.

6. A theft preventer for a vehicle comprising an alarm including an actuating part movable into and out of engagement with a moving part of the vehicle, connected vacuum chambers, a diaphragm in each chamber, connections between one diaphragm and said actuating part, means for moving the other diaphragm whereby to affect the first diaphragm, and means for releasably holding the parts in such positions.

7. A theft preventer for an automobile comprising a pair of connected vacuum chambers, a diaphragm in each of the cham-

bers, a horn including a diaphragm and a rotatable actuating member for vibrating the horn diaphragm and movable into and out of engagement with a moving part of the automobile, means holding the rotatable member normally out of engagement with the moving part of the automobile, means for moving one of the diaphragms whereby to

affect the other diaphragm to engage the actuating member with the moving part, ¹⁰ means for locking the parts in operative position, and means for moving the actuating member into engagement with the moving part upon breaking of the vacuum.

In testimony whereof, I affix my signature.

CASPER P. SEITZ.
